MILL

Edward A. Butler, Buffalo, N. Y., assignor to The
Turbuletics Corporation, Buffalo, N. Y.

Application March 30, 1938, Serial No. 198,945

4 Claims. (Cl. 83—13)

This invention relates to improvements in colloid mills or machines for the minute disintegration and/or comminution of otherwise immiscible substances.

It is generally well known and understood that mills for the minute disintegration of substances such as are used in connection with the preparation of emulsions, colloidal suspensions and dispersoids, may employ the principle of particle collision or impingement, and shearing action which may be set up in a thin layer of liquid carrying solid particles, as a result of rapid movement of the opposing sides of the layer in opposite directions. This action may be induced through adherence of the mill feed material to relatively moving mill surfaces. The moving members of mills of this type travel at high rates of speed and are usually provided with cylindrical, conical, or disc-like surfaces, the rapid rotation of which set up centrifugal forces tending to segregate the component elements of the mill feed materials according to different viscosity, specific gravity, or other physical characteristics. This centrifugalization tends to result in accumulation and packing of solid particles from the feed material against the walls of the mill and particularly in the region comprising the pre-milling chamber between the feed inlet and the zone in which the milling process actually takes place. Thus solid material tends to accumulate in the mill to a point where it contacts the moving member of the mill, and the friction resulting from this contact generates heat as a result of which the material may burn or melt, thus spoiling the product and/or clogging the mill.

Variations of temperature in mills of this type invariably cause alterations in the physical proportions of the various members of the mill, thus effecting the spacing between the relatively movable members and causing frictional heat and/or alteration of product sizes. Also in this type of machine the rapid rotation of the disc or conically shaped mill member in connection with the milling process has heretofore imposed centrifugal forces upon the material passing through the mill tending to increase the speed of the higher specific gravity particles through the mill, thus destroying the homogeneity of the yield and cutting short the milling action. It has therefore been difficult to provide a mill that would operate on many kinds of substances required for industrial purposes that is capable of yielding the desired product and performing with uniform results over extended periods of time.

One object of the invention is to provide a

mill construction in which reduction of particle size and/or dispersion of particles in emulsion products is effected in accordance with commonly accepted principles, but with increased efficiency of operation.

Another object of the invention is to provide in a colloid mill construction utilizing closely arranged relatively movable film carrying surfaces of the conical type an improved arrangement and disposition of parts whereby undesirable centrifugal action is obviated which would otherwise tend to speed the passage of material through the mill before completion of the disintegrating process.

Another object of the invention is to provide in a mill of this type means for preventing segregation of component elements of the mill feed material as a result of centrifugal action set up by the rotating members, and accumulation of solid particles upon the relatively movable members of the mill, thus obviating the possibility of frictional burning of the mill feed substances and/or clogging of the mill.

Another object of the invention is to provide in a fine grinding mill an improved construction embodying means for convenient adjustment of the relatively movable members to yield different sized products and to compensate for variations of the relative positions of the stationary and movable members thereof such as may result from temperature changes therein.

Another object of the invention is to provide an improved mill construction for treating fluids containing solids wherein concentration of the mill feed material in the milling zone may be controlled by an improved pressure regulating means conveniently positioned externally of the mill, whereby the rate of impingement action between the solids in the feed material may be regulated at will to control the degree of solid particle disintegration.

Another object of the invention is to provide an improved mill construction for treating normally immiscible liquid mixtures wherein the rate of impingement action between droplets of the liquids may be regulated to control the degree of droplet disintegration and comminution.

Another object of the invention is to provide in an improved mill construction of the type employing members movable relatively one to another at high rates of speed, means for preventing segregation of solids and/or liquid portions of the mill feed material as a result of centrifugal action, whereby the mill feed materials pass through the mill in a homogeneous state.

The invention is exemplified in a construction employing a generally funnel shaped shell or stator and a conically shaped rotor mounted concentrically therein for rotation relatively to the stator. A feed inlet is provided at the apex of the stator for introduction of the mill feed material between the opposed surfaces of the rotor and stator members. The apex portion of the rotor is provided with a plurality of mill feed diverting conduits which are in open communication with an axially disposed mill feed receiving conduit in line with the mill feed inlet to receive a portion of the incoming mill feed. The feed diverting conduits extend radially and laterally through the body of the rotor, and are thus adapted, by reason of centrifugal action set up by rotation of the rotor, to discharge streams of feed material laterally against the adjacent walls of the stator for disrupting any segregating tendency in the mill feed material prior to its passage between the milling portions of the rotor and stator, and to break up any accumulation of solid particles on the walls of the mill.

By-pass ports extending radially in spaced relation through the adjacent portions of the stator receive a portion of the laterally discharged feed material for conveyance through suitable connecting return conduits to the original source of mill feed supply, thus relieving excessive pressures in the premilling chamber.

The rotor is of the general shape of a cone generated by a line inclined at 15° to the longitudinal axis thereof, as it has been found as a result of exhaustive experiments that centrifugation forces resulting from the rapid rotation of a cone of this degree produces no appreciable segregation of the mill feed mixed materials or acceleration of the passage of heavier particles of the mill feed material through the milling zone.

The rotor and stator members are relatively mounted through means of articulated frame members in such manner that both parallel and inclined axial adjustment as well as lateral relative adjustments of fine degree may be made to provide uniform and accurate spaced relationships between the rotor and stator under varying conditions of temperature and wear. Means are provided for circulating either heating or cooling fluid mediums through the interiors of the stator and rotor members for controlling temperature conditions in the mill. An improved automatic, simple and effective lubricating means for the rotor bearings is provided.

In the drawings:

Fig. 1 is a fragmentary view, partly in elevation and partly in section, of the milling portion of an apparatus incorporating the invention;

Fig. 2 is a diagrammatic view of the complete apparatus;

Fig. 3 is a section, on an enlarged scale, through the pre-milling chamber and a portion of the milling zone of the mechanism shown in Fig. 1;

Fig. 4 is a view, partly in elevation and partly in section of another form of milling head and shaft construction;

Fig. 5 is a section taken substantially along line V—V of Fig. 1;

Fig. 6 is a section taken substantially along line VI—VI of Fig. 1.

Referring to the drawings, a frame member 10 is mounted upon a conventional type electric motor 12 by means of bolts 14 in such manner

that the motor provides a base for the device.

The motor base 12 is adapted to be arranged upon any suitable support such as a stand 16 (as shown in Fig. 2) for support upon a floor, or by suspension from above in any conventional manner. The frame 10 is in the form of a generally cylindrical upright casting, and rotatably carries therein a rotor shaft 30 by means of a pair of spaced bearings 32 and 33 respectively. At its lower end, the shaft 30 is connected to the extending end 40 of the armature shaft of 10 the motor 12 by means of a coupling 42 of the conventional flexible type.

The upper end of the shaft 30 is provided with a slightly tapered section 38 adapted to receive in tight-fitted relation thereon a centrally bored 15 rotor head member 50. The bore of the head 50 is tapered to correspond to the tapering of the section 38 of the shaft 30 for accurately and firmly positioning the head 50 upon the shaft 30. An intermediate portion of the head 50 is 20 provided with an enlarged bore as at 54 to allow for the unequal expansion of the material forming the head under varying temperature conditions, which might otherwise impose dangerous stresses in the material forming the head 50. 25 The head 50 is provided with a smoothly machined outer working surface 56 extending about the majority of the longitudinal extent of the head and tapered uniformly at an angle of approximately 15° from the longitudinal axis of 30 the head. As shown clearly in Figs. 3 and 4 immediately adjacent its upper end, the head 50 is provided with an increased degree of taper, as at 57.

A cap member 65 for the head 50 is provided 35 in the general form of a truncated cone and is provided in its lower portion with a central bore to receive the extreme upper end of the shaft 30 and a downwardly extending annular threaded portion 68 adapted for cooperation with a threaded recess in the upper end of the head 50. 40 Thus the cap 65 provides a closure for the upper end of the head 50. A lock nut 51 engages the upper threaded end portion 52 of the shaft 30, thus detachably maintaining the head 50 on the shaft 30. The lock nut 51 is formed with a laterally extending flange 53 at its lower end for bearing against a thrust ring 55 positioned in the head 50, thus limiting the upper movement of the lock nut 51.

To assemble the component parts of the milling head unit, the lock nut 51 is first inserted in the recess in the upper end of the head 50 and the thrust ring 55 is then threaded into its position, thus retaining the lock nut 51 in the head. The upper end of the shaft 30 is then inserted through the bore of the head 50 to a position wherein the threaded end 52 of the shaft engages the threads of the lock nut 51. The lock nut 51 is then rotated by means of a suitable wrench, thus drawing the threaded end of the shaft 30 into the lock nut and forcing the tapered section 38 of the shaft into the tapered central bore of the head 50 to a firmly seated position. The cap 65 is then threaded into position upon the upper end of the head 50, thus sealing the connection between the shaft and the head. To disassemble the milling head unit, the cap 65 is first removed and the lock nut 51 is then rotated by means of a wrench. The flange 53 of the lock nut bears upwardly against the thrust ring 55, and thus the unthreading movement of the lock nut generates longitudinal thrust forces between the head 50 and the shaft 30, thus forcing the shaft 30 out of the head. 75

The bearing members 32 and 33 are of a conventional ball bearing assembly type, each comprising an outer race 34, an inner race 35, and an intermediately disposed series of steel balls 36. Portions of the frame member 10 immediately adjacent the bearings 32 and 33 are provided with accurately machined annular surfaces to laterally position the outer bearing races 34. The inner races 35 bear laterally against correspondingly machined surfaces of the shaft 30. Shoulders 72 are provided on the shaft 30 for cooperation with upper and lower lock nuts 74 and 76 which are threaded upon the shaft 30 to maintain the inner races 35 in proper position longitudinally of the shaft. A pair of locking rings 78, threaded into the frame 10, bear against opposite ends of the outer races 34 to position the bearings 32 and 33 longitudinally with respect to the frame 10. Thus the shaft 30 is supported 20 in an upright position in the frame 10 for rotation relative to the frame.

A saddle piece 90 in the general form of a cylindrical casting is mounted upon the upper end of the frame 10 by means of a pair of spaced annular steps 98 and 102 formed on the frame 10 in such manner as to be concentric with the casing and the milling head and shaft. The saddle 90 is shaped at its lower end as an annular flange having a lower face 94 and an adjacent inner vertical face 96. Thus, the annular step 98 on the frame 10 is adapted to receive the flange of the saddle in close fitting relation thereon and to position the saddle 90 upon the frame 10 both laterally and longitudinally. A series of studs 100 arranged in radial spaced relation about the step 98 are provided to detachably maintain the saddle 90 in assembled position upon the frame.

The upper end of the frame 10 is formed with an annular flange 102 spaced at a substantial distance from the step 98 both longitudinally and laterally of the machine, being of smaller diameter than the step 98 and at an elevated position therefrom. A concentric annular vertical bearing surface 104 is formed on the adjacent portion of the saddle casting 90 for cooperation with the flange 102 to position the saddle 90 laterally with respect to the frame 10. Thus the saddle casting 90 is firmly supported upon the frame by a pair of supporting surfaces which are spaced one from another both laterally and longitudinally of the machine. Unequal longitudinal movements at opposite sides of the mill between the saddle 90 and the step 98 will alter the angular relation of the longitudinal axes of the saddle and the frame, the saddle pivoting upon the contact between the flange 102 and the bearing surface 104. Thus adjustments of the angular relation between the saddle 90 and the frame 10 may be accomplished by loosening the studs 100 and inserting suitable shims between the step 98 and the saddle at the proper points. Hence, variations from proper axial alignment of the frame and the saddle member such as may occur as a result of temperature changes or imperfect machining of parts, may be corrected.

The upper end of the saddle is internally threaded as at 112 to receive in threaded relation therein a stator milling member 120. The stator is of an outer cylindrical form, and is provided centrally with a longitudinal tapered bore. The central bore is accurately machined to provide a conical milling surface 122 which conforms to the general shape of the mill head 50. The stator 120 is adapted, by reason of its threaded

mounting in the saddle 90 for adjustment longitudinally of the mill to various spaced positions with respect to the milling head 50. Thus means are provided to vary the width of the milling gap between the surfaces 122 of the stator and 56 of the rotor. The threads 112 are formed in such manner as to be relatively loose fitting and to allow a small amount of lateral relative movement between the stator 120 and the saddle 90. A series of studs 130 arranged at intervals around the saddle 90 are threaded into openings through the saddle and are adapted to bear against the stator 120 to provide means for shifting the stator 120 laterally relative to the saddle. Lock nuts 131 hold the studs 130 in adjusted positions. Thus minor adjustments of the position of the stator may be made to compensate for improper alignment of the parts such as may be due to imperfect machining and/or operating temperature changes.

A locking ring 129 encircling the upper end of the stator 120 and in threaded relation therewith, provides means for accurately positioning and maintaining the stator 120 in parallel axial relation with the saddle 90 in every position of its adjustment.

A dome 132 of a generally cylindrical outer form and provided with a conically shaped central bore in the lower end thereof is mounted upon the upper end of the stator member 120 by means of bolts 133. A mill feed inlet port 134 is formed centrally through the upper end of the dome 132 and in open communication with the apex of the cavity in the lower end of the dome. The bore of the dome conforms to the shape of the tapered cap 65 of the milling head, and provides therebetween an annular pre-milling chamber for the even distribution of mill feed material from the inlet port 134 about the upper end of the milling gap between the surfaces 122 and 56 of the stator and the milling head respectively. The tapered portion 57 of the milling head 50 provides an intermediate step between the surface of the cap 65 and the surface 56 of the head to automatically provide a pre-milling gap of a width greater than that of the milling gap in every position of milling head adjustment.

The milling head cap 65 is provided with an axially disposed inlet port 60, extending from the upper or apex end thereof downwardly and in line with the mill feed inlet port 134 to an intermediate position in the cap where it joins in open communication with a plurality of radially disposed discharge ports 62 extending laterally to the outer surface of the cap. The inlet port 60 is of smaller dimension than that of the mill feed inlet port 134 of the dome. As shown in Fig. 3 a plurality of radially disposed by-pass channels 136 are formed through the dome 132 commencing from a position intermediate of the pre-milling chamber and extending to the outside of the dome 132 for connection with a manifold collecting conduit 140 which in turn communicates with the original mill feed supply tank 145 through means of a conduit 141. An inlet conduit 147 of conventional type conducts the liquid mill feed material to the mill in response to pressure generated by a pump 148 in the feed inlet line. A valve 142 is located in the line of the conduit 147 whereby the operator of the machine may regulate at will the fluid pressure within the mill. A gauge 143 is provided in the manifold 140 to apprise the operator of pressure conditions therein.

In operation, the milling head unit comprising the shaft 30, the head 50 and the cap 65 is rotated by means of the motor 12, and mill feed material is introduced into the dome 132 by operation of the pump 143. A portion of the mill feed material entering the pre-milling chamber between the conically-shaped surfaces of the cap 65 and the dome 132 travels downwardly toward the milling zone between the head 50 and the stator 120. The rapidly rotating movement of the milling head tends to impart a circular or spirally descending movement to this portion of the mill feed material as it passes through the pre-milling zone, and centrifugal forces set up in the feed material tend to cause segregation of the component parts thereof because of their different viscosities, specific gravities and/or other physical characteristics. Another portion of the incoming mill feed material, however, enters directly the port 60 of the cap 65, and travels downwardly and thence laterally into the discharge ports 62; and due to the centrifugal action set up by the rapid rotation of the cap, this portion of the feed material is impelled outwardly with great force through the ports 62 and is thrown transversely into the adjacent section of the pre-milling gap. Thus the rapidly rotating cap member 65 engages a portion of the incoming mill feed material, directs its course, and throws it outwardly in a circular path in a manner similar to the action of an impeller of a centrifugal pump.

As shown in Fig. 3, the by-pass ports 136 are so disposed in the dome 132 that they open into the pre-milling gap in positions substantially within the section of the pre-milling gap into which the ports 62 of the cap 65 discharge their portion of the feed material. The by-pass ports 136 are preferably so arranged, however, that the centers of their openings into the pre-milling gap are at points slightly above the center line of the discharge of the ports 62, so that the discharge from the ports 62 is divided into two courses, one of which enters directly the by-pass ports 136, and the other of which strikes the opposing wall of the dome 132 and is then deflected downwardly and into the milling gap of the machine.

As illustrated in Fig. 3, there is thus provided means for constantly disrupting any tendency of segregation of the mill feed material in the pre-milling gap due to centrifugalization or other cause, thus insuring the delivery of a homogeneous mixture of mill feed material to the milling gap of the machine. The rapid eruption of mill feed material from the discharge ports 62 across the pre-milling gap and toward the wall of the dome 132 also prevents deposits of solid substances against the wall of the dome 132 in such manner as might result in an accumulation of sufficient thickness to reach across the gap and contact the rapidly rotating milling head. Thus the dangers of frictional burning of the mill feed material, and development of undesirable mill temperatures and clogging of the machine are obviated.

The portion of the mill feed material passing through the by-pass ports 136 in the dome is returned by way of the conduit 141 to the original mill feed supply tank 145. The remainder of the incoming mill feed material travels downwardly into the milling zone between the surfaces 56 and 122 of the head 50 and stator 120 respectively. The stator 120 is adjustable vertically in the saddle 90 to provide the desired width of

mill gap between the milling surfaces, and the angular relation between the saddle and the frame 10 as well as the lateral and longitudinal relative positions of the stator in the saddle, are adjustable to obtain perfect conformity between the rotor and stator surfaces. Thus a gap width of the minutest degree may be established uniformly throughout the extent of the milling zone without frictional contacts between portions of the relatively moving members. Hence, prohibitive friction-generated heating of the mill is avoided, and a more uniformly fine product is obtained.

In the lower end portion of the saddle 90 an annular collecting trough 150 is provided to conduct the discharge from the milling zone to outlet ports 152 at opposite sides of the machine, from whence the mill product may be conveniently collected. A covering for the bearings 32 and 33 is provided by a flange 160 formed on the saddle 90 and adapted to encircle the shaft 30. The flange 160 is provided with a sealing ring 162 of conventional design, for preventing the passage of foreign material downwardly and past the flange into the bearings. A downwardly extending apron 164 is attached to the lower end of the milling head 50 by means of studs 165 and extends below the upper margin of the flange 160, thus preventing the return of material discharged from the milling zone upwardly and in toward the shaft 30 above the flange 160. A retaining plate 166 maintains the sealing ring 162 in operable position within the flange 160.

Means for lubricating the bearings 32 and 33 are provided by a bell-shaped slinger ring 170 fixedly mounted upon the shaft 30 below the bearing 33 by means of a sleeve 172 between the ring 170 and the bearing race 35. The lower laterally extending flange portion of the ring 170 is adapted to revolve in a well 176 provided in the frame 10 by an upturned flange 174. An up-take tube 178 is in open communication at its lower end with the well 176 and at its upper end with the annular chamber 180 formed between the flange 102 of the frame and the shaft 30 above the bearing 32. A supply of lubricating oil of sufficient quantity to fill the well 176 is introduced through an inlet connection 182 on the up-take tube. Rotation of the shaft 30 and the slinger ring 170 causes a constantly moving supply of oil to be forced upwardly through the up-take tube to its point of discharge above the bearing 32 in accordance with the principles of centrifugal action. The forces of gravity then cause the oil to work its way downwardly through the members of the bearing 32 and thence downwardly along shaft 30 to the bearing 33 and thence to return again to the sump 176.

Hand-hole plates 15 are provided in the sides of the frame member 10 to provide convenient means of access to the top of the motor 12 and the coupling 42. Air vents 17 are provided in the hand-hole covers 15 to assist in connection with the ventilation of the motor 12.

As illustrated in Fig. 1, means are provided to regulate the temperature of the stator 120 and the dome 132 as comprising a fluid conducting chamber 121 interiorly of the stator 120 and a similar fluid conducting chamber 135 formed interiorly of the dome 132. A fluid inlet conduit 190 is provided for introducing a constantly running supply of fluid into the lower section of the chamber 121 of the stator. An outlet port 191 formed in the upper end of the stator 120 communicates with an inlet port 192 through the

wall of the dome 132, and an outlet port 193 is provided through an opposite wall portion of the dome 132 for connection with a discharge conduit means of any conventional type. Thus a temperature-regulating fluid may be circulated through the stationary working members of the mill. In some cases this will be a cooling fluid to prevent the building up of excessive temperatures in the mill; and in some cases the fluid will be a heating medium to maintain the mill at a temperature prerequisite to the proper handling of certain materials.

Fig. 4 illustrates a form of milling head construction identical with that shown in Fig. 1 except that in addition, means for regulating the temperature of the milling head are provided. A duplex packing gland 200 embraces the lower end of the shaft 30 in liquid tight relation by means of packing rings 202. An inlet port 204 is in open communication with an annular liquid chamber 206 which is formed jointly by a wall of the gland and the adjacent portion of the shaft 30. The shaft 30 is provided with a central longitudinal bore in which is fitted a section of double compartment tubing 208, thus defining a pair of separate longitudinal openings 210 and 211 through the shaft. The opening 210 is in open communication with the fluid inlet chamber 206 by means of a port 212. The milling head 50 is provided with an interior chamber 214 for fluid containing purposes. A port 216 is in open communication with the opening 210 and the chamber 214 is provided in the lower section of the head, and a port 218 in the upper end of the head provides communication means between the chamber 214 and the upper end of the shaft opening 211. At its lower end, the longitudinal opening 211 is in open communication by means of a port 219 with an outlet chamber 220 and an outlet connection 221. Thus a cooling or heating fluid medium may be forced through the inlet 204 and upwardly through opening 210, and thence circulated throughout the interior of the milling head 50 and returned through the longitudinal opening 211 and discharged through the outlet connection 220 while the mill is operating, to assist the fluid circulating through the stator in controlling the temperature of the mill.

Although only one form of the invention has been shown and described in detail it will thus be apparent to those skilled in the art that the invention is not so limited but that various changes can be made therein without departing from the spirit of the invention or from the scope of the appended claims.

I claim:

1. A mill for disintegrating substances comprising a fixed member having a truncated cone-shaped working surface, a rotatable member having a truncated cone-shaped working surface closely adjacent the first mentioned surface and defining a milling path for the mill feed material therebetween, the apex portions of said fixed and rotatable members providing a pre-milling chamber adjacent the inlet ends of said working surfaces for distributing mill feed material evenly into said milling path, a mill feed material inlet at the apex of said fixed member for discharging mill feed material into said pre-milling chamber axially of said mill, by-pass conduits formed in the apex portion of said rotatable member for receiving a portion of the mill feed passing through said inlet and diverting it transversely of said mill axis and impelling it across said pre-milling chamber as a result of centrifugal

action set up by rapid rotation of said rotatable member, and radially disposed outlet ports through the walls of said fixed member in the region of the pre-milling chamber for receiving a portion of the mill feed material passing through said inlet and conducting said portion of said mill feed material to the original mill feed supply.

2. A mill for fluid materials comprising inner and outer cone-shaped members in telescopic relation and relatively movable about a coincident longitudinal axis and defining a milling path therebetween, a mill feed material inlet adjacent the apexes of said members for discharging mill feed material axially of said mill and into said milling path, a by-passing conduit through the inner of said members having an inlet port in line with said mill feed material inlet and adapted to receive a portion thereof and to divert it from said milling path, said by-passing conduit having another portion adapted to redirect said by-passed portion of said mill feed material and to discharge it into said milling path in a direction transversely thereof, and a radially disposed outlet port through the wall of the outer of said members adapted to receive a fraction of the mill feed material discharged by said by-pass conduit and conducting said fraction of said mill feed material to the original feed supply.

3. A mill for fluid substances comprising a fixed member having a truncated cone-shaped working surface, a rotatable member having a truncated cone-shaped working surface closely adjacent the first mentioned surface and defining a milling path for the mill feed material therebetween, an inlet for said mill feed material at the apex of said fixed member working surface in the form of a conduit of circular section having a discharge opening so arranged as to introduce the mill feed material into the mill in a direction axially of said mill, and a conduit in said rotatable member having a mill feed receiving opening of circular section at the apex thereof and in line with said discharge opening, the diameter of said receiving opening being substantially less than the diameter of said discharge opening, said rotatable member conduit being adapted to receive a portion of said mill feed material under dynamic pressure forces and to divert it away from the milling path between said working surfaces and to subsequently redirect and impel said diverted portion of said mill feed material transversely across said milling path and against the walls of said fixed member.

4. A mill for fluid substances comprising a fixed member having a cone-shaped working surface, a rotatable member having a cone-shaped working surface closely adjacent the first mentioned surface and defining a milling path for the mill feed substances therebetween, means for introducing mill feed substance between said working surfaces including an inlet conduit at the apex of said fixed member working surface having a discharge opening directed axially of said mill, and conduit means in said rotatable member having an inlet opening in line with said fixed member inlet conduit opening of substantially lesser sectional area than the latter for receiving a portion of the mill feed material under dynamic pressure forces and diverting it away from the milling path and subsequently directing said diverted portion of said mill feed material transversely of said milling path.
